UNITED STATES PATENT OFFICE.

FREDERICK MOMBURG, OF YBOR CITY, FLORIDA.

METALLIC FABRIC.

965,314.

Specification of Letters Patent. Patented July 26, 1910.

Original application filed January 8, 1910, Serial No. 537,014. Divided and this application filed February 21, 1910. Serial No. 545,130.

To all whom it may concern:

Be it known that I, FREDERICK MOMBURG, a citizen of the United States, residing at Ybor City, in the county of Hillsboro and State of Florida, have invented certain new and useful Improvements in Metallic Fabrics, of which the following is a specification, reference being had to the accompanying drawings.

10 This invention relates to certain new and useful improvements in metallic fabrics and has for its object to provide a fabric or covering of this character which is particularly adapted for purposes of ventilation and is 15 designed for the protection of horticultural products from the heat of the sun while at the same time affording ample ventilation.

Another object is to provide a metallic fabric which may be applied to a large number 20 of useful purposes and is simple in construction and extremely strong and durable in use.

With these and other objects in view, the invention consists of the novel features of 25 construction and the combination and arrangement of parts hereinafter fully described and claimed, and illustrated in the accompanying drawings, in which—

Figure 1 is a plan view illustrating a 30 section of metallic fabric constructed in accordance with the present invention; Fig. 2 is an enlarged longitudinal section taken on the line 2—2 of Fig. 1; and Fig. 3 is a section taken on the line 3—3 of Fig. 1.

35 Referring more particularly to the drawings, 5 indicates the sheet-metal bars or plates of my improved fabric or covering. These plates are adapted to be arranged in parallel relation, the longitudinal edges 40 thereof being spaced, as shown at 6. Wires 7 are arranged alternately upon opposite sides of the plates 5 and are likewise disposed in spaced parallel relation. Wires 8 extend centrally between the spaced longitudinal edges of the metallic plates 5 and are interwoven with the wires 7, as clearly 45 shown in Fig. 3, whereby an interlaced wire structure is formed having the metallic plates 5 arranged therein. It will be obvious 50 that this arrangement of the wires and plates may be indefinitely extended and the fabric formed in any desired width or length. The extremities of the plates 5 are turned over upon the wires 7 in opposite 55 directions, and closely engage with the faces

of the plates. In this manner the plates are adapted to be rigidly secured against sliding movement between the wires 8, and this is the only means which has been found necessary in order to secure these plates in the 60 interlaced wires 7 and 8.

While my improved metallic fabric or covering is especially designed and adapted to be used upon plant protecting sheds of that character shown and described in my 65 pending application for patent filed January 8, 1910, Serial Number 537,014, of which this application is a division, it will, of course, be understood that there are a large number of other useful purposes to which 70 my invention might well be put. I have found such a fabric particularly desirable for the protection of sensitive plants from the rays of the sun, while at the same time they are afforded ample ventilation and 75 sufficient sunlight for their proper cultivation.

It will be noted that the spaces between the longitudinal edges of the parallel plates 5 are comparatively narrow, and the wires 80 7 which are interwoven with the wires 8 again divide the space into half. These wires, however, do not restrict the entrance of the sunlight to any material extent.

It will be obvious that when in use, narrow bars of sunlight will be admitted to the structure or inclosure in which the plants are grown, a comparatively wide shadow separating each bar of sunlight. The width of the metallic plates and the gage of the 85 wires are regulated in accordance with the idiosyncrasy of the plants being grown, whereby they may be carefully nursed and the best possible results thus assured to the grower.

90 The fabric may be easily secured upon the frame of the protecting shed, is indestructible by fire, is not affected by the sun's rays, and will not readily deteriorate by exposure to rains or hard usage.

100 Having thus described the invention what is claimed is:

1. A fabric of the character described, comprising a plurality of comparatively wide metallic plates having their longitudinal edges arranged in spaced parallel relation, and two series of parallel wires arranged at right angles to each other and interwoven, the wires of one series extending 105 at right angles to the plates, the alter- 110

nate wires of said series being disposed upon one side only of the plates and of the wires of the other series.

2. A fabric of the character described, comprising a plurality of comparatively wide metallic plates having their longitudinal edges arranged in spaced parallel relation, and two series of parallel wires arranged at right angles and interwoven, the 5 wires of one series being centrally disposed between the opposed edges of the plates, the 10 wires of the other series extending at right

angles to the plates and disposed alternately upon one side only of said plates and alternately extending under the wires of the 15 other series which are arranged between the plates.

In testimony wherof I hereunto affix my signature in the presence of two witnesses.

FREDERICK MOMBURG.
